UNITED STATES PATENT OFFICE.

CHARLES E. WOOD, OF ST. ALBANS, WEST VIRGINIA.

MITER-BOX.

1,241,804.

Specification of Letters Patent.

Patented Oct. 2, 1917.

Application filed September 13, 1916. Serial No. 119,900.

To all whom it may concern:

Be it known that I, CHARLES E. Wood, a citizen of the United States, residing at St. Albans, in the county of Kanawha and State 5 of West Virginia, have invented certain new and useful Improvements in Miter-Boxes, of which the following is a specification.

This invention relates to an improved miter-box and has as its primary object to 10 provide a device of this character employing a saw guide adjustable for making miter cuts of various angles and wherein the box proper of the device will also be adjustable for imparting obliquity to the miter cuts.

15 The invention has as a further object to provide a device of this character wherein the angle of the miter cut may be determined with accuracy and also wherein equal accuracy will be had in determining the inclination of the bevel to be imparted to the miter cut.

20 The invention has as a still further object to provide a device of this character wherein, as above intimated, an obliquely directed miter cut may be made at one operation.

25 Other and incidental objects will appear as the description proceeds and in the drawings wherein I have illustrated the preferred embodiment of the invention and wherein similar reference characters designate corresponding parts throughout the several views:

Figure 1 is a front elevation of my improved device particularly showing the manner in which the sides of the miter box proper are cut away to receive the saw,

35 Fig. 2 is an end elevation particularly showing the adjustable mounting of the box proper, and the operating lever provided with a catch for holding the said box at adjustment,

40 Fig. 3 is a horizontal sectional view particularly showing the construction of the base or stand of the device and the adjustable mounting of the saw guide,

45 Fig. 4 is a fragmentary sectional view on the line 4—4 of Fig. 3 and particularly showing the manner in which the saw guide is connected with the base,

50 Fig. 5 is a detail vertical sectional view of one of the posts of the saw guide and the pawls carried thereby for automatically locking the saw in elevated inactive position.

55 Fig. 6 is a fragmentary perspective view

particularly showing the construction of the saw back to coöperate with the pawls carried by the posts of the saw guide,

Fig. 7 is a fragmentary sectional view 60 more particularly showing the mounting of the said pawls,

Fig. 8 is a perspective view showing one of the pawls detached,

Fig. 9 is a detail perspective view showing 65 the type of angle members employed to fit in the cut away portions of the sides of the box proper for guiding the saw in any instance where it is desired to make right-angled cross cuts only, and

Fig. 10 is a fragmentary perspective view 70 showing the angle members mounted in active position upon the box.

In carrying out the invention, the device is formed with a base or stand including 75 coacting arcuate body members 10 having suitable supporting legs and joined by spaced parallel connecting bars 11 secured at their extremities in any approved manner to the said members. The end members 10 are rabbed or channeled to slidably receive arcuate angle plates 12 having the laterally directed flanges 13 thereof terminating flush with the outer faces of the members 10 with the extremities of the said plates respectively 85 secured to the sides 14 of the miter box proper adjacent the ends of the box. Coacting with the plates 12, are arcuate locking plates 15 and 16 therefor. These locking plates are connected to the outer faces of 90 the body members 10, as by bolts or other suitable fastening devices and are provided with laterally extending flanges 17 overlying the flanges 13 of the plates 12 for slidably connecting the said plates with the 95 base. The plates 12 thus provide supporting plates for the box proper with the said plates shiftable upon the body members 10 of the base for adjustably rotating the box about its longitudinal axis with respect to 100 the base. Connected to one end of the box proper is an operating lever 18. This lever, at its upper extremity, is provided with suitable arms, as more particularly shown in Fig. 2 of the drawings, connected to the 105 sides 14 of the box with the lever depending in front of the locking plate 16. This plate, at its outer extremity, is provided with an arcuate outwardly projecting toothed flange 19 and pivotally mounted 110 upon the lever 18 to coöperate with the said flange, is a pawl 20. This pawl is, as shown

in Fig. 3 of the drawings, provided with a tooth 21 projecting freely through the body of the lever 18 and normally urged to engage the teeth of the flange 19 for automatically locking the box proper at adjustment.

The supporting plate 12 adjacent the lever 18, is, as more particularly shown in Fig. 2, provided upon its outer face and adjacent each end of the said plate with a scale 22 each indicating 90° of the circle in which the box proper is mounted to swing, with the said scales each beginning at zero at the adjacent side of the box. Consequently, either one scale or the other, depending upon which one is exposed, may be consulted when adjustably swinging the box about its center. The sides 14 of the box are arranged at substantially right angles to each other and at a point substantially midway the ends of the said box, the said sides are notched or cut away in the usual manner as shown at 23 for receiving the saw. As will be best observed upon reference to Fig. 1 of the drawings, the box is provided with a depending loop at the inner extremities of said notches to provide a clearance for the saw when the box is swung about its axis. The side walls 14 of the box, at the end thereof opposite the lever 18, are preferably arranged to overhang the base for receiving the lumber or work and the said walls at the adjacent extremity of the box are also preferably equipped with work clamps 24 carried by screws 25 swiveled in suitable lugs projecting laterally from the outer faces of the box walls with the clamps 24 extending through slots in the said walls to engage the work.

Extending between and connecting the bars 11 at a point substantially midway the ends of the base, is a horizontally arranged arcuate bearing plate 26 provided at its inner circumference with an upstanding annular flange 27. Rotatably mounted upon the said plate is a saw guide including an annular body 28 freely surrounding the flange 27 to rest upon the plate 26 and formed, at diametrically opposite points, with radial arms 29 and 30. Connected to the upper edge of the flange 27, at opposite sides thereof, are locking plates 31 which, as shown in detail in Fig. 4 of the drawings, bear over the body 28 of the guide for holding the said guide upon the bearing plate 26. The arm 30 which extends forwardly from the base is formed at its outer extremity with a handle 32 to the under side of which is pivotally connected a locking pawl 33 provided, at its inner extremity, as more particularly shown in Fig. 2, with a tooth normally urged to coöperate with a toothed arcuate plate 34 connected at its extremities to the outer side of the adjacent connecting bar 11 of the base to project laterally there-

from beneath the arm 30. The arm 30, adjacent its outer extremity, is provided with an opening 35 above the bar 34 and projecting into this opening, is a pointer 36. The bar 34, upon its upper side is provided with a scale 37 reading from each side of the longitudinal center of the bar toward the ends thereof and indicating upon each side of the said center 45° of the circle around which the saw guide is mounted to swing. The pointer 36 is arranged to coöperate with the scale 37 and may be observed through the opening 35 so that by manually operating the pawl 33, the saw guide may be accurately adjusted about its axis, to either one side or the other of a position at right angles to the box proper.

The arms 29 and 30, adjacent the extremities thereof, are formed with suitable openings in which are mounted upstanding hollow posts 38 connected at their lower extremities with the said arms by suitable collars 39. Each of the posts 38 is, as shown in detail in Fig. 5, provided with a longitudinal slot 40 for receiving the saw and carries, adjacent its upper extremity, a pair of coacting pawls 41, one of which is shown in detail in Fig. 8. The pawls 41, at their inner extremities, are provided with transverse sleeves 42 fitting between the sides of the post and receiving pivot pins 43 with the said sleeves acting to center the pawls within the post. At their upper extremities, the pawls 41 are provided with flat shoulders 43 from which extend inwardly beveled shoulders 44 converging toward their inner extremities with the inner edges of the said pawls sloping upwardly and inwardly toward each other, as shown at 45 toward the inner ends of the shoulders 44. Connected to the upper extremities of the pawls and bearing at their free ends against the sides of the post are springs 46 normally urging the pawls toward each other to active position.

Slidable longitudinally upon the posts 38 are sleeves 47 held against upward displacement by cap screws 48 threaded upon the upper ends of the posts. The sleeves 47 are slotted to freely receive the saw 49 and slide upon the posts 38 in the usual manner as the saw is raised or lowered. The saw 49 is provided with a rigid back 50 embracing the upper margin of the saw body and providing at its inner extremity, lateral shoulders 51 extending in opposite directions from the sides of the saw. Formed in opposite sides of the saw back 50, at suitable longitudinally spaced points, are inwardly beveled notches 52.

As will now be seen, when the saw 49 is elevated to inactive position upon the posts 38, the saw back 50 will ride over the curved edges 45 of the pawls 41 to spring the pawls apart and permit the saw back to

assume a position above the upper ends of the said pawls. Upon the passage of the saw back 50 between the pawls, the springs 46 will then urge the pawls inwardly to engage the upper ends thereof or the shoulders 43 beneath the shoulders 51 of the saw back for automatically locking the saw in elevated position. To release the saw, the handle thereof is grasped and the saw shifted longitudinally until the notches 52 in the saw back 50 are, as shown in Fig. 2, disposed above the upper ends of the pawls 41. The beveled bottom walls of the said notches will then engage between the beveled shoulders 44 of the said pawls to spring the pawls outwardly when the weight of the saw will then serve to release the pawls and permit the lowering of the saw upon the posts 38 to active position.

10 5 I consequently provide an arrangement wherein, upon the movement of the saw to inactive position, the said saw will be automatically locked in such position and wherein the said saw can be released only 20 by shifting the saw into a predetermined relation with respect to the posts 38. Consequently, the saw will not likely become accidentally released to drop and cause possible injury to the operator.

30 35 40 45 50 From the preceding description, it will now be understood that the saw guide may be shifted to adjust the saw with respect to the box proper for making miter cuts at various different angles while the said box may be rotated upon the base through the medium of the lever 18 for varying the obliquity of the said cuts. By consulting either of the scales 22, the oblique inclination of the cut may be accurately determined. Moreover, by employing a scale at each end of the adjacent supporting plate 12, one of the scales may be adjusted with reference to one end of the plate for positioning the adjacent side of the box proper to a predetermined angle when the angle then assumed by the opposite side of the said box will be indicated by the other scale. Accordingly, bevels of two different oblique angles may be cut, according to which side of the box is employed to receive the work, at one adjustment of the box.

In some instances, it may be desired to make only cuts at right angles to the box and when it is intended to so use the device, 55 I have provided auxiliary guide members 53 for the saw. These guide members are, as best shown in Fig. 9 of the drawings, each triangular in general contour and are arranged within the notch 23 in the side 14 of the box proper farthest from the operator with the confronting edges of the members defining a slot as shown in Fig. 10 for receiving the saw. The guide members 53 are, upon the outer sides thereof, formed 60 with a plurality of lugs 54 while the sides 14 of the box proper are provided with similar lugs adapted to mate therewith for detachably receiving suitable pins 55 holding the guide members in position. Consequently, for the ordinary use of the device, 70 these guide members may be easily displaced.

It will, therefore, be seen that I provide a particularly efficient construction for the purpose set forth and an arrangement 75 wherein miters of various angles may be cut while, at the same time, said miters may be given an oblique direction which may be easily varied in degree.

Having thus described my invention, what 80 I claim and desire to secure by Letters Patent is:

1. A device of the character described including a base, a box carried thereby, and a saw guide mounted upon the base, the said saw guide including a body member, upstanding posts carried thereby, sleeves slidable upon said posts and formed to operatively receive a saw, co-acting pawls carried by the posts, and yieldable means bearing between the said pawls and the posts and normally urging the pawls to position for engagement with the back of a saw for automatically locking the saw in inactive position upon the elevation thereof upon the 95 posts.
2. A device of the character described including a base, a box mounted thereon, and a saw guide carried by the base, the said guide including a body member, upstanding 100 posts mounted upon the body member, sleeves slidable upon the said posts, and pairs of coacting pawls carried by the said posts respectively with the pawls of each pair formed adjacent the upper extremities 105 thereof with inwardly converging shoulders, the said sleeves being adapted to operatively receive a saw having a back providing lateral shoulders at opposite sides of the saw and formed at longitudinally spaced points 110 with inwardly beveled notches with the saw movable with the said sleeves with respect to the posts to position the saw back above the upper ends of the pawls to be automatically engaged thereby with the said ends of 115 the pawls coacting with the shoulders of the saw back for supporting the saw in inactive elevated position with respect to the box and with the saw movable with respect to the said sleeves for disposing the said notches to 120 receive the beveled shoulders of the said saw back whereby the saw may be moved downwardly for spreading the pawls to disengage the saw back whereby the saw may be lowered to active position.
3. A device of the character described including a base, a box carried thereby, a saw guide mounted upon the base, said saw guide including a body member, upstanding posts carried thereby, and co-acting locking means 130

carried by the said posts, and a saw mounted upon the posts and provided with a back, the saw being shiftable upwardly upon the posts to engage the back thereof with the said means for locking the saw in inactive position with the saw back formed to bear between the said locking means for permitting the release of the saw.

4. A device of the character described including a base, a box carried thereby, a saw guide mounted upon the base, the said saw guide including a body member, upstanding posts carried thereby, and co-acting pawls mounted upon said posts, and a saw mounted upon the posts and provided with a back having notches formed therein, the saw being shiftable upwardly upon the posts to engage the back thereof between the said pawls for locking the saw in inactive position with the saw movable to position the said notches to receive the pawls for permitting the release of the saw.

5. A device of the character described including a base, a box carried thereby, a saw guide mounted upon the base, the said saw guide including a body member, upstanding posts carried thereby, co-acting pawls carried by said posts, and means normally urg-

ing the said pawls to active position, and a saw mounted upon the posts and provided with a back, with the saw shiftable upwardly upon the posts to engage the saw back with the pawls for locking the saw in elevated position, the said saw back being formed at spaced points to bear between the pawls of the said posts for separating the pawls against the tension of said means and permitting the release of the saw.

6. In a device of the character described, the combination with a saw guide including upstanding posts and coacting locking means carried thereby, of a saw mounted upon the guide and including a saw back, the saw being shiftable upwardly between the said locking means to engage the back of the saw with the said means for locking the saw in elevated position upon the posts, and oppositely inclined shoulders formed on the sides of the saw back with the saw shiftable longitudinally to engage the said shoulders between the upper ends of the said locking means to spread the said means and permit the release of the saw.

In testimony whereof I affix my signature.

CHARLES E. WOOD. [L.s.]
